UNITED STATES PATENT OFFICE.

ROSCOE W. BARE, OF SPRINGFIELD, ILLINOIS.

SOCKET WRENCH FOR FORD AUTOMOBILES.

Application filed September 4, 1924. Serial No. 735,801.

This invention relates to a class of combination socket wrench such as may be ordinarily needed about automobile motors for manipulating bolts and nuts on the same.

5 A particular object of my invention is to provide a combination socket wrench of the character herein described and claimed and which in its merited design is adapted to provide easy access to several of the more difficult recesses about the more recent models of Ford automobiles and more particularly such places as the retaining bolts for the carburetor and the starter generator.

15 A further object of my invention is to provide a combination socket wrench of the character herein described which in the nature of its design is adapted to provide an arrangement whereby the hand power controlling the movement of the wrench may be applied in the same pivotal plane in which the point of application of the wrench to the bolt or nut is the center thus removing the usual cause for socket wrenches slipping off the bolt head or nut; especially in 20 such inaccessible places about the car motor as may make it impossible to get any extra hand pressure on top of the wrench to help hold the wrench from slipping.

25 The desired object of my invention is attained by the socket wrench for Ford automobiles, described in the annexed specifications, recited in the claim and illustrated in the accompanying drawings in which like reference numerals indicate the same structural parts in the several figures.

30 In the drawings Fig. 1 is a perspective of the wrench of my invention. Fig. 2 is a side elevation of the wrench of my invention. Fig. 3 is a top view of the wrench of my invention. Fig. 4 is a sketch showing 35 how the wrench may be successfully used in close places about a car motor that are not easily accessible where satisfactory results may be obtained with this wrench without any difficulty.

40 The preferred embodiment of my invention is illustrated in the several figures above mentioned and the desired means of operating the same will be clearly set forth 45 in the instructions which follow.

50 Referring now to the structural detail of my invention it will be observed that the sockets on opposite ends of the wrench for the sake of convenience should be of unlike size and a size in each case which will be the 55 most practical for the greatest number of

bolts or nuts that are likely to be found about the motor of a well known automobile and more particularly such bolts and nuts as are not easily accessible because of some mechanical obstruction that may stand in the way of securing a satisfactory grip with a wrench of ordinary design. 60

It is a matter of common experience among automobile mechanics to find certain parts of the motor in such a position with respect to the bolt or nut desired to be worked on that it is with the greatest difficulty that the mechanic is able to secure a firm wrench grip on the head of a bolt or nut 65 without the wrench slipping off and it is with this difficulty in mind that the inventor who is a practical mechanic has designed the wrench which is the subject of this application. 70

75 In this connection it seems that where previous efforts have been made to design a socket wrench which would reach the more inaccessible bolts and nuts that the handles for such wrenches have been formed in such a way that where the hand power is applied for normally turning the bolt that the direction of movement and the relative position of the hand in turning the wrench has had a tendency to cause the wrench socket to slip 80 off of the bolt head even in spite of efforts that have been commonly made in such cases to hold the wrench down securely on the bolt head by means of the hand not used in turning the wrench. 85

90 It is to be further observed in this respect that when the mechanic is working in such close places and manipulating a wrench with one hand he can usually get better results by having one hand free with which to balance his poise instead of having to use his free hand for exerting pressure down on the wrench to keep it from slipping off the bolt head. 95

100 The novel design of the socket wrench of my invention will prevent the difficulties above mentioned for the reason that it is designed on scientifically correct mechanical principles of operation.

105 Referring to the details of construction, a method of manufacture of a wrench of this character would be to form the knobs 6 and 7 and sockets 1 and 2 at corresponding ends of a straight handle after which handle 3 is bent near the ends to form the wrench necks 4 and 5 respectively parallel with each other and at right angles to the handle 110

—3— and on the same side of the straight body portion.

It will now be noted that when the wrench is thus formed and ready for use the mechanic may use the wrench with great satisfaction in difficult situations about the type of car for which it is best adapted.

For instance referring to Fig. 4 if the mechanic desires to tighten a cap screw 8 with this wrench in a difficult place about the motor 9 he may for example place wrench socket 2 over the head of cap screw 8 where wrench neck 4 and handle 3 make integral connection with neck 5 and knob 6 at the opposite end of the wrench which are jointly used normally as a hand grip for the mechanic when turning the cap screw 8 in which case the knob 6 is adapted to normally fit snugly into the mechanic's hand in manipulating the wrench.

It will be seen from the foregoing description of the wrench of my invention that when the hand power of the mechanic is applied to knob 6 moving the wrench in an arc about a central axis located at the longitudinal center of cap screw 8 that the exerted hand pressure being in the same pivotal plane with the said cap screw head will properly poise the wrench socket over the cap screw head and thus have a tendency to hold the wrench on the cap screw without the necessity of exerting extra pressure on the wrench in order to hold it down on the cap screw, a thing which is very difficult to do in places that are not easily accessible about the car motor.

It will be observed that when a mechanic

is working in close places under or around a Ford car motor and is using a wrench he usually needs one hand on the wrench and the other for stabilizing his poise and this is particularly true where it becomes necessary to manipulate the retaining cap screws holding the carburetor, the starter generator, connecting rod nuts, crank case bolts and nuts, manifold studs, dust pan nuts, differentials, housing nuts, universal joint bolts and nuts and so on.

I do not wish to be confined to the use of hexagonal sockets as shown for sake of convenience and existing use on present car models but it will be seen that the same merits will hold good where square sockets are used or square headed bolts, nuts and studs.

Having thus described the nature of my invention what I claim as new and useful and desire to secure by Letters Patent is:

A wrench comprising a straight body portion having integral arms carried by the ends of said body portion at substantially right angles thereto in parallel relation to each other on the same side of said straight body member and in the same plane as the body portion and provided with nut receiving recesses in their ends, said arms of equal length forming handle members when either arm is in engagement with a nut, whereby a leverage action may be applied to the nut in the plane of the nut.

In witness whereof, I hereunto set my hand and seal, this 21st day of August A. D., 1924.

ROSCOE W. BARB. [L. S.]
